UNITED STATES PATENT OFFICE.

WEBSTER R. WALKLEY, OF BROOKLYN, N. Y., ASSIGNOR OF ONE-HALF TO
THE PECK, STOW & WILCOX COMPANY, OF SOUTHBURY, CONN.

DESIGN FOR AN INKSTAND-FRAME.

SPECIFICATION forming part of Design No. 14,807, dated February 19, 1884.

Application filed December 24, 1883. Term of patent 7 years.

To all whom it may concern:

Be it known that I, WEBSTER R. WALKLEY, a citizen of the United States, residing at Brooklyn, in the county of Kings and State of New York, have invented and produced a new and original Design for an Inkstand-Frame, of which the following is a specification, reference being had to the accompanying drawings, forming part thereof.

10 Figure 1 is a perspective view of my newly-designed inkstand-frame. Fig. 2 is a perspective view of the ink-well for which my frame is adapted, and Fig. 3 is a side elevation of said frame and ink-well properly placed together.

The leading feature of my design consists of the frame formed in the representation of a chair.

15 *a* designates the legs of my inkstand-frame A. 20 *b* designates the bars, which represent the arms of a chair, having upward projections *c*, of the form shown, and which constitute the pen-rack.

d designates a seat-like portion having its edges curved downward, as shown, and provided with a central opening of a square form, corresponding in shape to the lower part of the ink-well B.

The ink-well is designed to be placed upon and within the seat-like portion *d*, as shown in Fig. 3.

The particular design for the ink-well is no part of this invention, and is only shown as one which is adapted to my frame, in order to illustrate said frame as it will appear in use.

35 I claim—

The design for an inkstand-frame herein shown and described, the same consisting of the frame A, formed in the representation of a chair.

WEBSTER R. WALKLEY.

Witnesses:

WINFIELD D. WALKLEY,
S. HOWARD WILCOX.
